UNITED STATES PATENT OFFICE.

FRANCIS K. FASSETT, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,047,775.

Specification of Letters Patent. Patented Dec. 17, 1912.

Application filed October 29, 1906. Serial No. 341,101.

To all whom it may concern:

Be it known that I, FRANCIS K. FASSETT, a citizen of the United States, residing at Dayton, in the county of Montgomery and State of Ohio, have invented certain new and useful Improvements in Cash-Registers, of which I declare the following to be a full, clear, and exact description.

This invention relates to time recorders and the principal object is to provide an improved construction of time stamp which may be used alone or as an attachment to a cash register. In case it is used as an attachment a novel winding mechanism shown herein may be employed controlled by the usual cash safe such as the cash drawer. In this connection a novel over-winding preventing mechanism is also employed.

A further object is to provide an improved construction in time stamps for printing A. M. and P. M. or for printing successive days.

With these and incidental objects in view, the invention consists in certain novel features of construction and combination of parts, the essential elements of which are set forth in appended claims and a preferred form of embodiment of which is hereinafter described with reference to the drawings which accompany and form part of this specification.

Of said drawings: Figure 1 is an elevation of the time stamp showing it attached to a register. Fig. 2 is a section taken just inside the frame piece shown in Fig. 1, and looking in the reverse direction, the section being on line 2-2 of Fig. 3. Fig. 3 is a plan of parts shown in Fig. 2 and also showing the amount printing type wheels. Fig. 4 is a detail section showing the winding mechanism for the clock and the printing devices. Fig. 5 is a rear view of Fig. 4 showing the overwinding preventer. Figs. 6 to 9 inclusive are views of a modification of the time controlled mechanism; Fig. 6 being a front elevation; Fig. 7 being a plan of the minute disk; Fig. 8 a plan of the hour disk and Fig. 9 a detail of the two type wheels.

This invention comprises a novel means for producing a differential motion which may be used in cash registers, adding machines and like devices. It is shown herein as controlling time printing wheels but with small change may be used in the manner

above indicated. The time stamp may be used alone or may be used as an adjunct in the nature of an attachment to a cash register and it is so shown herein.

The machine to which the invention is shown as applied is a well known type disclosed in prior patents among which may be mentioned patents to Joseph P. Cleal 693,498, Feb. 18, 1902; 718,565, January 13, 1903; and 786,346, April 4, 1905. The first of these patents shows a key operated cash register having two counters and a set of operating keys common thereto. The control of the counters as to which one shall be in operative relation with the actuating devices is provided for by a push button or key. In the second of the patents referred to a machine of the same type is shown but with the addition of printing devices. The last above patent shows the same machine but with two cash drawers instead of one, the cash drawers being also controlled by the push button above referred to. To the machine shown in the said patents I have applied a time stamping device together with means for winding the clock thereof.

For a full description of the cash register, the above patents are referred to but in general it may be said to comprise a series of operating keys which when depressed serve to actuate one of two registers, the register which is to be operated being determined by a push button. The keys control the movement of a common member known as a key coupler and this member serves in its oscillation to cause a complete rotation of a shaft. In this attachment the said shaft serves to operate the platen and to cause a movement of the time printing wheels to desired position. A clock is of course provided to control the time stamping and automatic means for winding the same are furnished, this means being operated by the return of either one of the cash drawers to normal position. A novel means for preventing over-winding of the clock by the operation of the drawers is also provided.

In prior patents time stamps attached to a register have been disclosed but they have been open to the objection that the clock is compelled to perform too large an amount of work. A clock spring has of course only a limited amount of energy stored therein and is not competent to continually drive a plurality of type wheels. To overcome this

difficulty in the present invention only graduated disks are driven directly by the clock and this causes little more work than is employed in driving the ordinary clock hands. The graduated disks serve to merely control the movement of the type carriers which are set from normal position at each operation by the actuation of the register itself.

10 Referring now to Figs. 1 and 2 it will be noted that the driving shaft above referred to as being given a rotation at each operation of the machine is indicated on Fig. 1 by the numeral 12. This shaft 12 carries 15 mounted eccentrically thereon a roller 13 which rides in a slot 14 of a bent arm 15. This arm is guided by slots 16 and 17 in a main frame piece 18. It will be seen that when shaft 12 is given a rotation the bent arm 15 will be moved toward the rear of the machine and then forward again to its normal position. Mounted in the forward end of bar 15 is a pin 19 passing through the slot 17 of the frame 18 and inside the frame 25 and mounted on this pin 19 are two gear wheels 20 shown in Figs. 2 and 3. Meshing with each of the two gear wheels 20 are racks 21 and 22, rack 21 being above the gear 20 and rack 22 being below the gear 20. These four racks, two for each gear, are carried by pin 25 at the forward ends said pin passing through slots 26 in all four bars and by pins 27 at the rear ends, the upper 30 one of which carries the upper rack bars 21 and the lower one of which carries the lower rack bars 22. It will be seen that when the gears 20 are moved bodily by the rotation of shaft 12 that they will tend to move all 35 four of the rack bars 21 and 22 toward the rear of the machine.

40 The clock mechanism may be of any well known type and is only indicated generally as it is not part of the present invention. Any mechanism which will drive the shaft 45 31 on Fig. 2 at one rotation per hour will answer and in fact by using a different ratio of gearing a different period of rotation of shaft 31 might be used. A gear 32 on this shaft meshes with a large gear 33 the ratio 50 of the two gears being such that gear 33 is rotated once in twelve hours. Adjacent to this gear 33 and rigidly secured thereto are two sets of graduated disks 35 for the minutes and 36 for the hours. The unitary 55 structure thus formed is free to revolve upon the shaft 34. Two sets of complementary disks for hours and minutes are provided as shown in Fig. 2 and two of the rack bars referred to are adapted to engage the hour 60 disks and the other two to engage the minute disks. The graduated disks 35 are complementary graduated as shown in Fig. 2 so that the sum of the radial distances from the center to the graduation is constant for any 65 pair of complementary steps. The rack bars

21 and 22 are positioned just outside and in the planes of the graduated disks and the distances from the ends of the pair of rack bars to the graduations on the disks 35 and 36 are constant. This readily follows from the complementary nature of the graduated disks. The disks 36 are graduated in the same way except that the steps have each an extent equal to one of the sets of steps of the minute disks. It will be seen from this construction that when the shaft 19 carrying gears 20 is moved rearwardly the pair of rack bars 21 and 22 adapted to engage the minute disks 35 will be projected until one of them strikes the step of a pair farthest from the center of the disk. This rack bar will then be stopped and the further motion of shaft 19 will rotate the gear 20 and thereby advance the other rack bar until it abuts the complementary step of the other disk 35. It will be clearly seen that with this construction it is only necessary to provide a second rack on one of the rack bars and to connect the time printing device with this. In the construction shown rack bars 22 are provided with additional racks 37 which gear with pinions 38. The pinion 38 for the hour wheel is sleeved about a shaft 39 which directly carries a similar pinion 38 for the minute wheel, these wheels being shown in Fig. 3 and indicated by numerals 41 and 42. The object of providing the complementary disks is to furnish a positive stop for a time printing mechanism. It was stated that when the shaft 19 moved bodily, both the rack bars 21 and 22 would also move and this would be the case if mechanism was not provided to detain one of the bars. It is however desirable to prevent movement of the time printing device and the rack bar 22 therefor until the rack bars 21 have been moved to abut the graduated disks 35 and 36. To accomplish this a pawl 42 engages in a notch 43 of the minute bar 22. This merely acts as a detent for the said bar and will only prevent its movement until its associated bar is stopped by the graduated disk. In a case of the hour printing devices a spring 44 connected at one end to the rack bar 37 and at the other end to the machine frame serves to prevent movement of the hour rack bar 37 until its associated bar has been stopped by the step on one of the disks 36. Either the pawl 42 or the spring 44 may be used on each rack bar. The former is preferred however because its retarding influence practically ceases after the rack bar starts while the spring exerts a constantly increasing resistance. The mechanism has been described as if the rack bars themselves directly abut the graduated disks but this is not strictly true as determining plungers 47 are pivoted at 471 at one end to the rack bars and their free ends are carried in hanger 49. Hanger 49 is free to move either up or down 130

but is held in a central position by blocks 49^a and spring 50 connecting said blocks which are mounted on the main frame by pins as shown.

- 5 The mechanism as thus far described operates as follows: When the cash register keys are depressed shaft 12 is given a complete rotation. This serves through roller 13 and bent arm 15 to move the shaft 19 first 10 rearwardly and then forwardly. The rearward movement of shaft 19 causes gear 20 to rotate as well as to be moved bodily for the reason that the gear meshes the rack bars 22 which are held in normal position by the 15 pawl 42 and the spring 44. The rotation of gear 20 serves therefore to move forwardly the rack bars 21 and the determining plungers 47 connected thereto until said plungers are stopped by one of the complementary 20 disks 35 and 36. Such stopping overcomes the retaining force of pawl 42 and spring 44 and rack bars 22 immediately move forward until their plungers 47 abut the other pair of disks 35 and 36. This last motion is communicated 25 to the type wheels and serves to set the same to position to print the correct time and it will be clear from the complementary nature of the graduated disks 35 and 36 that the ends of plunger 47 will in 30 all cases be moved until they strike the steps of the disks thus furnishing a positive stop for the time wheels. The mechanism would be operative with only one disk 35 and one disk 36 but would be liable to overthrow.
- 35 As the mechanism is shown it is adapted to print the time at intervals of five minutes. The graduated disks 35 and 36 have only a very slow rotation so that the passage of a step from the plane of movement 40 of the plungers 47 takes considerable time. To insure the printing of the proper time one of the plungers 47 is beveled on its rearward end as indicated at 48, this will clearly serve to slightly elevate the set of plungers 45 as they are all carried in a frame 49 which is spring supported as indicated at 50 on the main frame it being noted that the beveled projection 48 is adapted to engage the disk 35 whose steps as they pass the plane of 50 plungers 47 successively increase in distance from shaft 34. The bevel of the plunger 47 as referred to has a function in setting the A. M. and P. M. type which will be hereafter referred to.
- 55 A novel mechanism for printing A. M. and P. M. is provided and this may be next described.

- The unitary structure consisting of gear 33 and disks 35 and 36 which as before stated 60 makes one rotation in twelve hours carries a pinion 51 engaging a gear 52 of twice the number of teeth, this gear being carried by a pin 53. Mounted on the gear 52 is a pin 54 which rides in a slot in an arm 55 on a pin 56^a 65 of the main frame. As gear 52 rotates once

in twenty-four hours it will be clear that arm 55 oscillates back and forth once in the same time. At the lower end of arm 55 it is connected to two springs 56 and 57 which are both connected to a curved bar 58. This 70 bar is mounted to slide forwardly and reversely and is connected at its forward end to an arm 59 mounted on a pin 60 and which has on the lower curved end thereof two type 61 and 62 for A. M. and P. M. The 75 bent arm 58 carries a lug 63 which is adapted to ride against a flange 33^a carried by and rotated with the gear 33, said flange having one small portion thereof cut away. It will be seen that as gear 33 rotates thereby driving gear 52 the arm 55 will be gradually moved rearward from its position in Fig. 2 thereby tensioning spring 57 and tending to retract the bar 58 and the type carrying arm 59, however the lug 63 rides against 80 the flange 33^a before referred to and thereby prevents the movement of the type carrier until the end of a twelve hour period. At this time however the broken away part of the said flange reaches lug 63 and spring 57 85 can then draw the arm 58 rearwardly, the lug 63 passing through the broken away portion of the flange 33^a, and thereby bringing type 62 to the printing point. During the 90 next twelve hour period the arm 55 is moved forwardly tensioning spring 56 and at the end of the said period a reversal of the described operation takes place as the broken away part of the flange 33^a again reaches lug 63 which thereupon moves forwardly 95 under tension of spring 56 restoring type 61 to the printing point. It will be evident that as flange 33^a rotates once only in twelve hours, its motion is very slow and it would be impractical to time the action of the lug 100 63 in its passage through the broken away portion of the flange so as to be certain such passage would occur precisely at the proper time. In order to insure the passage of the lug 63 through the cut away portion of the 105 flange 33^a at the proper moment, so as correctly to record the time, the upper bevel portion 48 of the plunger 47, which engages with the disk 35 whose graduations increase in distance from the center as the disk passes 110 the plunger while moving counter clockwise, will engage the radial portion of the highest point on the disk 35 upon the operation of the machine and thereby be slightly depressed. This depressing of the plunger 115 47, which only occurs at five minutes past noon and midnight, depresses a hanger 49 which in turn depresses the link 58 thereby carrying the lug 63 in position to be drawn through the cut away portion of a flange 120 33^a by either of the springs 56 or 57. This control of the A. M. and P. M. type-carrier by other parts of the time printing mechanism is very essential from the fact that if left to be operated by the springs 56 and 57 125 130

there is a possibility of the lug 63 remaining in contact with the flange 33^a when it should pass through the cut away portion of said flange thereby printing 12.05 A. M. or P. M. 5 when it should record just the opposite. When the time printing type carriers have been adjusted the amount printing carriers 71 have also been set as described in the patents referred to and the impression is then 10 taken from both sets of carriers. The shaft 12 carries a cam 72 which serves to depress the platen arm 73 against the tension of a spring 74. This platen arm 73 carries a platen 75 and when the high point of the cam 72 passes the projection 76 of platen arm 73 the said arm will rise under tension 15 of spring 74 and force any record material against the type carriers. In this mechanism the record material is a paper strip 20 shown in Fig. 1 and is mounted on a roller 77 passing thence over pins 78 and 79 to a winding roller 80. A pawl 81 serves to drive a feeding ratchet 82, this pawl being oscillated with the key coupler which is carried 25 on shaft 83. The ratchet 82 is geared through a pinion 84 to a gear 85 which serves to feed an ink ribbon 86. This ribbon passes around the roll 87 moved by the pinion 85 and also passes over other supporting rollers as shown. It will be seen 30 that the record strip is fed slightly at each operation and that a fresh portion of the ink ribbon is brought to printing position at each operation.

35 As before stated means are provided for automatically winding the clock. The machine is provided with two cash drawers only one of which is shown and in the rear of each of the drawers is a lever 101. These 40 levers are carried one tightly and one loosely by a shaft 102 shown in Figs. 1 and 4. The loose lever 101 has connected rigidly thereto a forwardly extending projection 103 and thereby connected rigidly with the other lever 101 is a second projection 104 extending slightly farther than the projection 103. Connected 45 by a pin to each of the projections 103 and 104 are pawls 105 shown in Fig. 5 adapted to both engage the wide ratchet 106. Springs 107 serve to rock the levers 101 forwardly and springs 108 serve to 50 press the pawls 105 against a ratchet 106. It will be seen that when either 55 of the drawers is open the corresponding lever 101 will move forwardly thereby retracting its pawl 105 over the teeth of the ratchet 106 and when the drawer is again closed the pawl 105 will rotate the said 60 ratchet the distance of one tooth. A usual retaining pawl 109 serves to prevent reverse rotation of the ratchet. This ratchet 106 is rigidly carried by a threaded shaft 107^a and to the other end of this shaft is attached 65 one end of the clock spring. The outer end

of the spring is attached to a barrel 110 and this is connected to the main driving gear 111 of the clock mechanism, the barrel of course being loose on the threaded shaft 107^a. A nut 112 is threaded on the shaft 70 107^a and has a flange 113 against which ride lugs 114 of a lever 115 pivoted on a long pin 116 and spring pressed against flange 113. The lower end of the lever 115 is adapted to move over the projections 103 and 104 and prevent their upward movement at the proper time. The lower end of the lever 115 serves to stop projection 103 and a flange 116^a thereof moves over and stops the projection 104, it being noted that projection 103 does not extend far enough to strike flange 116^a. A ratchet 106 is rotated the spring is wound by turning its central shaft and the nut 112 thereof moves along the shaft by the threads thereof, this nut being connected to the gear 111 by a pin 118 passing through the nut and therefore preventing its rotating with the shaft 107^a. As the nut moves along the shaft the lever 115 will follow it under its spring tension 90 thereby bringing the lower end of the lever and the flange 116^a thereof finally over the projections 103 and 104 of the winding levers 101. When this happens the movement of the cash drawers will no longer wind the 95 clock as the levers 101 do not move outwardly to retract pawls 105 over the teeth of ratchet 106. As the clock operates however the gear 111 rotates and the nut 112 rotates with it through the medium of pin 118. This rotation of nut 112 serves to move it reversely along the threaded shaft 107^a and will finally carry the lever 115 so far that the lower end thereof and the flange 116^a are moved out of the path of 100 projections 103 and 104. If the machine is now operated winding will again take place. It will be seen that this mechanism provides an automatic winding device for the clock actuated every time the machine is operated and at the same time serves to prevent over-winding in a very simple manner. It may be noted that with the mechanism shown fifteen operations of the cash 105 register per day will serve to keep the clock wound and of course in practice many more operations than this number would be given the machine so that there is no danger of the clock running down.

To provide for setting the graduated 110 disks 35 and 36 there is provided an additional disk 121 shown in Fig. 1 having a graduated dial thereon adapted to pass close by the pointer 122 which serves to adjust the device. As is usual in clock mechanisms the shaft 31 is driven frictionally and so may be turned by hand without disturbing the clock.

The modification shown in Figs. 6 to 9 inclusive is a little simpler than the mech- 130

anism of the other disks, and does away with the separate A. M. and P. M. type carrier. The clock driven shaft 31^a of the modification is intended to be rotated once in an hour and instead of carrying one gear 32 which drives both sets of disks there are provided two gears 32^a and 32^b and two sets of disks for hours and minutes separately on shaft 34^a. As the mechanism is shown 5 the pinion 32^a is for the minute disk and 32^b for the hours disk. The pinion 32^a has twenty teeth and gears with a large gear having one hundred and eighty teeth so that the large gear receives one rotation every 10 nine hours. The gear 32^b for the hours disks has eight teeth and gears with a large gear having one hundred and ninety two teeth thereby giving said gear a rotation once in twenty four hours. These ratios 15 of gearing are not required and any ratio which will move the graduated disks properly will answer, it being only necessary that the minute disks shall move to pass one set of graduations in an hour and the hours 20 disk to pass one step in the same period. The hours disks 36^a are as stated given a rotation once in twenty four hours and two sets of complementary graduations are provided. One set however is more distant 25 from the center of the disk than the other set by the distance of one half of a step. This construction serves to provide that the type wheel for the hours may be set to any of twenty four positions instead of twelve 30 as in the other form, so that the A. M. and P. M. type may be carried on this wheel as shown in Fig. 9 there being two numerals for each of the hours one having the A. M. type beside it and the other the P. M. 35 type and one being set to printing position when A. M. should be printed and the other set when P. M. should be printed.

The mechanism is shown as adapted to set time printing wheels but it is obvious that 40 the invention may be applied to perform other functions for example if the graduated disks are set by hand or by a series of keys to any desired position and the machine operated, the wheels instead of printing time may be used to print amounts, 45 thus serving to form a cash recorder. The rack bars 37 again, may well be used to actuate a registering apparatus instead of printing wheels as herein shown.

50 The mechanism just described is shown and described as performing the above mentioned functions in application No. 394,186, filed September 23, 1907, by the present applicant, and all claims common to the two 55 applications are to be embodied in the later one, the present case being limited to the time recording mechanism.

While the form of mechanism here shown and described is admirably adapted to fulfil 60 the objects primarily stated, it is to be

understood that it is not intended to confine the invention to the one form of embodiment herein disclosed, for it is susceptible of embodiment in various forms all coming within the scope of the claims which follow. 70

What is claimed is as follows:

1. In a printing mechanism, the combination with printing devices and means for taking impressions therefrom, of a time printing type wheel, a clock mechanism, graduated disks driven by said clock mechanism, a rack for operating said time printing type wheel, a pinion meshing with said rack, and means for moving said pinion bodily and thereby actuating said rack. 75

2. In a device of the class described, the combination with a plurality of differentially movable members geared together, of clock controlled means for obstructing movement of one of said members and thereby 80 throw the geared connection correspondingly effecting movement of the other of said movable members, and recording mechanism operated by said latter member. 85

3. In a printing mechanism, the combination with printing devices, and means for taking impressions therefrom, of a clock mechanism, and graduated disks driven thereby, rack bars connected to said printing devices, and means for positively actuating 90 said rack bars to an extent dependent on said graduated disks and thereby driving said printing devices to set up the time determined by the graduated disks. 95

4. In a printing mechanism, the combination with type carriers, and means for taking impressions therefrom, of a clock mechanism and graduated members driven thereby, devices positively moved to engage 100 said graduated members, and connections whereby movement of said devices actuates said type carriers to a corresponding extent. 105

5. In a printing mechanism, the combination with printing devices, and means for taking impressions therefrom, of a clock mechanism and graduated elements controlled thereby, devices positively moved at 110 each operation from a constant normal position to an extent depending on said graduated elements, and connections whereby said printing devices are actuated as said positively moved devices are operated. 115

6. In a printing mechanism, the combination with printing type carriers, and means for taking impressions therefrom, of racks for moving said type carriers, a clock mechanism and graduated elements driven thereby, and means for positively moving said racks to extents dependent on said graduated elements and thereby actuating said type carriers. 120

7. In a printing mechanism, the combination with printing type carriers and means for taking impressions therefrom, of sliding racks permanently connected to said type 130

6
carriers, a clock mechanism and graduated elements controlled thereby, pinions gearing with said rack bars and movable to drive said rack bars to extents dependent on said graduated elements, with means for positively moving said pinions.

8. In a printing mechanism, the combination with printing type carriers, and means for taking impressions therefrom, of graduated time controlled members, driving devices permanently connected to said type carriers with means for positively moving said driving devices to extents dependent on said time controlled members and thereby differentially adjusting said type carriers.

9. In a printing mechanism, the combination with printing type carriers, and means for taking impressions therefrom, of time controlled mechanism, driving racks geared to said type carriers, pinions engaging and operating said driving racks, and means for giving said pinions invariable excursions.

10. In a printing mechanism, the combination with a clock mechanism, and graduated devices controlled thereby, of time printing type carriers, slidable racks permanently connected to said type carriers, and means for positively sliding said racks to extents dependent on said graduated devices and thereby differentially positioning said type carriers.

11. In a printing mechanism, the combination with a clock mechanism and graduated disks controlled thereby, of time printing type carriers, a fixed axis around which said type carriers rotate, racks engaging and driving said type carriers, and means for positively moving said racks past said carriers to extents dependent on said graduated disks and thereby setting the type-carriers in position to print the time.

12. In a printing mechanism, the combination with time controlled mechanism including graduated elements, of time printing type carriers, slidable racks connected to drive said carriers, and means for positively sliding said rack past said carriers and thereby differentially adjusting said type carriers.

13. In a printing mechanism, the combination with a printer, type carriers, of time controlled mechanism including a pair of complementarily graduated elements, racks and connections for engaging said graduated elements, connections whereby one of said racks drives said type carriers, and a pinion connecting said racks with means for giving said pinion invariable excursions.

14. In a printing mechanism, the combination with a printing type carrier, of time controlled mechanism including graduated disks, racks and connections for engaging said graduated disks, teeth carried by said racks for driving said type carrier, a pinion

engaging said rack, and means for bodily shifting said pinion invariable extents.

15. In a printing mechanism, the combination with time printing devices and clock mechanism governing the movement of the same, of a lever for winding said clock mechanism, means comprising a laterally movable arm for obstructing said lever, and devices controlled by said clock mechanism for moving said arm.

16. In a printing mechanism, the combination with a time printing mechanism, and clock mechanism, including a threaded winding shaft, for controlling said printing mechanism, of a lever for actuating said winding shaft, and a detent moved laterally by the windings of said shaft and serving to prevent operation of said lever when the clock mechanism is wound.

17. In a machine of the class described, the combination with graduated disks and means for adjusting them to various positions, of determining members, sliding rack bars engaging said determining members and slidable to actuate said members to extents dependent on said graduated disks, and means for positively actuating said rack bars.

18. In a time recorder, the combination with graduated elements, and time controlled means for adjusting them to different positions, of rack bars and determining members movable thereby, a gear meshing with each rack bar and having a constant excursion at each operation of the machine, and other rack bars also meshing with said gears and movable thereby to an extent determined by the graduated elements.

19. In a time recorder, the combination with rack bars and time controlled means for obstructing them after any desired travel thereof, of additional rack bars, determining members controlled by the additional rack bars, a gear meshing with each two rack bars and means for giving said gears a constant excursion at each operation of the machine.

20. In a printing mechanism, the combination with time controlled mechanism, of time printing type carriers and means for taking impressions therefrom, racks positively geared to said type carriers to rotate said carriers when said racks move, and means for positively actuating said racks to extents dependent on said time controlled mechanism and thereby setting the type-carriers in position to print the time.

21. In a printing mechanism the combination with time controlled members complementarily graduated, of rack bars, one for each member, gears connecting said rack bars in pairs, time printing devices driven by one of each pair of rack bars and means for giving said gears a constant excursion at each operation of the machine.

22. In a printing mechanism, the combination with time controlled members complementarily graduated, of rack bars one for each member, gears connecting said rack bars in pairs, time printing devices connected to one of each pair of rack bars, yielding detent means holding said connected rack bars, and means for giving said gears a constant excursion at each operation of the machine. 5
23. In a printing mechanism, the combination with time controlled mechanism having a rotation in twelve hours, of a type carrier having A. M. and P. M. type, a gear controlling same and so connected to the time controlled mechanism as to rotate in twenty four hours, and connecting means between said gear and type carrier arranged to be obstructed until the end of a twelve hour period. 10
24. In printing mechanism, the combination with time controlled mechanism, making one rotation in twelve hours, of a type carrier having A. M. and P. M. type thereon, a gear connected to the time controlled mechanism so as to rotate in twenty four hours, connecting said means between said type carrier and gear arranged to be put under tension by the movement of the gear, and a flange on said time controlled mechanism but having a cut away portion for obstructing the movement of said connecting means until the completion of a twelve hour period. 15
25. In printing mechanism, the combination with time controlled mechanism comprising graduated disks, of time printing devices, rack bars controlling said devices and arranged to be actuated to contact with said graduated disks, one of said bars having its contacting end beveled for the purpose described, and means for moving said bars. 20
26. In a machine of the class described, the combination with a clock controlled mechanism comprising a pair of graduated disks, of a printing type carrier, a pair of rack bars and a driving pinion connecting said bars, connections from one of said bars to said type carrier, and means for bodily shifting said pinion and thereby driving said rack bars. 25
27. In a machine of the class described, the combination with a graduated element and time controlled means for giving it varied positions, of a type carrier and a rack bar for driving it, a second rack bar having connections for engaging said graduated element and a pinion connecting said two rack bars with means for bodily shifting said pinion. 30
28. In a machine of the class described, the combination with time controlled mechanism including a pair of complementarily graduated disks, of a type carrier, a pair of slides, one of which has connections for driv- 35
- ing said type carrier, means permanently connecting said slides, and devices for moving said connecting means to actuate said slides to an amount depending on said graduated disks. 40
29. In a machine of the class described, the combination with time controlled differentially adjustable determining means, of a type carrier, a pair of slides and connections from one of said pair for driving said type carrier, means permanently connecting said slides, and devices for moving said connecting means to actuate said slides to extents depending on the adjustment given said determining means. 45
30. In a machine of the class described, the combinations with graduated elements and clock mechanism for driving same, of slides and connections pivoted thereto and positioned to engage said graduated elements, one of said connections having a beveled engaging end, and a pivoted hanger supporting said connections and permitting sidewise movement of all said connections, means for moving said slides, and printing type carriers controlled by said slides. 50
31. In a machine of the class described, the combination with time controlled graduated elements and a flange movable therewith and having a cut away portion, of slides having connections for engaging said graduated elements, type carriers controlled by said slides, an additional type carrier, and means controlled by said flange and its cut away portion for adjusting said additional type carrier. 55
32. In a machine of the class described, the combination with time controlled graduated elements and a flange movable therewith and having a cut away portion, of slides having connections for engaging said graduated elements, one of said connections being beveled as described, type carriers adjusted by said slides, a pivoted hanger supporting said connections, and constructed to be depressed by the beveled connection, an additional type carrier, and spring operated devices controlled by said flange for adjusting said additional type carrier, said devices being positioned to be depressed by said hanger. 60
33. In a time recorder, the combination with an operating mechanism having a constant excursion during each operation of the time recorder, of time controlled graduated elements, a plurality of type-carriers, and rack bars positively geared at all times with the operating mechanism and controlled by the graduated elements for differentially adjusting the type-carriers upon an operation of the time recorder. 65
34. In a time recorder, the combination with an operating pinion having a constant excursion during each operation of the time recorder, of time controlled graduated ele- 70

ments, a type-carrier, and complementarily movable slides positively geared at all times with the pinion and controlled by the graduated elements for differentially adjusting the type-carrier upon an operation of the time recorder.

35. In a time recorder, the combination with a clock controlled mechanism, of a type-carrier having A. M. and P. M. characters thereon, springs for moving said type-carrier in opposite directions to bring the characters thereon into printing position, and means controlled by the clock controlled mechanism for energizing said springs.

36. In a time recorder, the combination with a clock controlled mechanism, of a type-carrier having A. M. and P. M. characters thereon, springs for moving said type-carrier in opposite directions to bring the characters thereon into printing position, means actuated by the clock controlled mechanism for energizing said springs, and a device connected to the clock controlled mechanism for preventing the operation of the type-carrier by its springs until the proper time.

37. In a time recorder, the combination

with a clock controlled mechanism, of a type-carrier having A. M. and P. M. characters thereon, and means controlled by the clock controlled mechanism for moving the type-carrier in opposite directions to bring the characters thereon into printing position.

38. In a time recorder, the combination with printing devices and clock mechanism governing the movement of same, of winding devices for the clock mechanism, and means for locking the winding devices, the said locking means being controlled by the clock mechanism.

39. In a time recorder, the combination with operating devices and clock mechanism governing the movement of same, of winding devices for the clock mechanism, and means controlled by the condition of the clock mechanism for locking and unlocking the winding devices.

In testimony whereof I affix my signature in the presence of two witnesses.

FRANCIS K. FASSETT.

CARL W. BEUST.

Copies of this patent may be obtained for five cents each, by addressing the "Commissioner of Patents, Washington D. C."

It is hereby certified that in Letters Patent No. 1,047,775, granted December 17, 1912, upon the application of Francis K. Fassett, of Dayton, Ohio, for an improvement in "Cash-Registers," errors appear in the printed specification requiring correction as follows: Page 4, line 82, for the letter "A" read *As*; page 5, line 86, for the word "throw" read *through*; page 6, line 100, strike out the words "of the machine;" same page, lines 111-112 and line 130, for the words "of the machine" read *of said means*; page 7, lines 9-10, for the words "of the machine" read *of said means*; same page line 27, first occurrence, strike out the word "said"; and that the said Letters Patent should be read with these corrections therein that the same may conform to the record of the case in the Patent Office.

Signed and sealed this 28th day of January, A. D., 1913.

[SEAL.]

C. C. BILLINGS,

Acting Commissioner of Patents.
